UNITED STATES PATENT OFFICE.

FREDERICK W. HILL, OF BOSTON, MASSACHUSETTS, ASSIGNOR TO THE CHANDLER ADJUSTABLE CHAIR AND DESK COMPANY, OF SAME PLACE.

DESIGN FOR A FURNITURE-SUPPORT.

SPECIFICATION forming part of Design No. 27,272, dated June 29, 1897.

Application filed February 2, 1897. Serial No. 621,699. Term of patent 7 years.

To all whom it may concern:

Be it known that I, FREDERICK W. HILL, a citizen of the United States, residing at Boston, in the county of Suffolk and State of Massachusetts, have invented and produced a new and original Design for Furniture-Supports; and I do declare the following to be a full, clear, and exact description of the same, reference being had to the accompanying drawings, forming a part thereof.

The design relates to furniture-supports of the kind composed of two members, an upper and a lower one, the former usually termed the "furniture-shank" and the latter termed the "base portion."

Figure 1 is a front elevation of the furniture-support, showing my design and showing the two above-mentioned parts as assembled; and Fig. 2 is an edge view of the same. The leading feature of the design of the upper member A consists in two parallel bars A' A', between which is an open elongated space A'', as shown in Fig. 1. At the top of the parallel bars A' A' are arms a' a', extending outward from the upper ends of said bars.

From the outer ends of the arms a' a' spring ribs a'' a'', made continuous in their lower ends with the bars A' A'. A³ A³ are approximately triangular openings bounded by the parts A', a', and a'', as shown in Fig. 1.

30

The leading feature of the design for the lower member B consists in two parallel bars B' B', between which is an open elongated space B'', as shown. The lower ends of the parallel bars B' B' are made continuous with an inverted or curved arch b''. (Shown in the drawings.) Continuous with the lower ends of the parallel bars B' B' are outwardly-flaring curved side extensions B³ B³, as shown in Fig. 1.

35

What I claim is—

The design for furniture-supports herein shown and described.

In testimony whereof I have affixed my signature in presence of two witnesses.

FREDERICK W. HILL.
